UNITED STATES PATENT OFFICE.

CARL LUND, OF PORT ORCHARD, WASHINGTON.

DESIGN FOR A KETTLE-SPOUT.

50,625.

Specification for Design.

Patented Apr. 17, 1917.

Application filed November 20, 1915. Serial No. 62,659. Term of patent 14 years.

To all whom it may concern:

Be it known that I, CARL LUND, a citizen of the United States, residing at Port Orchard, in the county of Kitsap and State of Washington, have invented a new, original, and ornamental Design for a Kettle-Spout, of which the following is a specification, reference being had to the accompanying drawing, forming a part thereof.

Figure 1 is a perspective view of the kettle spout; and

Fig. 2 is a side elevation showing the spout attached to a kettle showing my new design.

What I claim as new and desire to secure by Letters Patent is:—

The ornamental design for kettle-spout as shown.

CARL LUND.
